UNITED STATES PATENT OFFICE.

WILLIS W. FRANTZ, OF WAYNESBORO, PENNSYLVANIA.

ELECTRIC CLOCK.

SPECIFICATION forming part of Letters Patent No. 691,256, dated January 14, 1902.

Application filed May 13, 1899. Serial No. 716,687. (No model.)

To all whom it may concern:

Be it known that I, WILLIS W. FRANTZ, a citizen of the United States, residing at Waynesboro, in the county of Franklin and State of Pennsylvania, have invented certain new and useful Improvements in Electric Clocks, of which the following is a specification.

My said invention consists in various improvements in the construction and arrangement of parts of electric clocks, whereby their operation is rendered certain and the construction simple and inexpensive, all as will be hereinafter more fully described and claimed.

Referring to the accompanying drawings, which are made a part hereof, and on which similar characters of reference indicate similar parts, Figure 1 is a rear view of a clock embodying my said invention, partly in elevation and partly in section; Fig. 2, a vertical section through the same looking in the direction indicated by the arrows from the dotted line 2 2 in Fig. 1; Fig. 3, a top or plan view 25 of the electric-circuit maker and breaker; Fig. 4, a detail cross-section on the dotted line 4 4 in Fig. 1, illustrating the regulating-valve more clearly; and Fig. 5, a detail view on the dotted line 5 5 in Fig. 2, showing the 30 clutch mechanism.

In said drawings the portions marked A represent the framework; B, the main operating wheel or ring, and C a scale electrically connected to alarm or call bells, as will be 35 presently described.

The frame A is of any suitable form and construction for the purpose, being especially adapted to the support and operation of the particular mechanism employed.

The main operating-wheel B is a hollow ring, preferably of glass, partially filled with liquid mounted to revolve on a shaft 1 and divided at its lower side at the center into two chambers b' and b² by the valve b. Said 40 valve is of any approved construction capable of fine adjustment for the purpose to be presently described. A by way or passage B' connects the two sides or chambers of the wheel. Said passage is located just below the center of said wheel, and a clip b⁶ is secured around its center, provided with upwardly-projecting ears with perforations,

through which the shaft 1 extends. To one side of said clip is secured a toothed wheel 2, and alongside said toothed wheel is a toothed 55 ratchet-wheel 3, secured to the shaft 1. A spring-pawl p is pivoted on the wheel 2 and engages with the teeth of the ratchet-wheel 3. The hollow ring B and wheel 2 are secured together, as above described, to turn freely 60 on the shaft 1, and the ratchet 3 is secured to revolve with the shaft. A toothed rack-bar 4, mounted with its upper end to slide in a guide a' on the frame A, engages with the teeth of wheel 2 and at its lower end is jointed 65 to one end of a pivoted lever 5, the opposite end of which lever is provided with an armature m and located near the positive pole of a magnet 6, which is an electrical circuit adapted to be opened and closed alternately, as will 70 be presently described. On the top of wheel or ring B is a metal plate B², having a vertical rib b⁴ extending diagonally from one end thereof to the other. A line-wire 7 runs from one end thereof to the magnet 6. On one side 75 of the vertical rib b⁴ the metal plate B² is covered with a strip of vulcanite or other non-conducting material b⁵. A spring-contact arm 9 is mounted in the frame above the plate B² and extends down, so that its point will 80 normally contact with the surface of said plate and be vertical when in its central position. From the upper end of said arm a line-wire 10 runs to one pole of a battery 8, and a wire 11 runs from its other pole to the other pole of 85 magnet 6. A weight W is connected by a flexible connection 12 to one side of the wheel B, said flexible connection being attached to its periphery at one side by a pin p' and extending entirely around to the same side and having the weight hung thereto. The valve v, which divides the wheel or ring into two chambers, consists of a diaphragm having an aperture covered by a plate mounted to slide thereon and operated by means of a fine adjusting-screw. This or any appropriate valve may be used, the only essential being that it shall be capable of fine adjustment in order that the proper regulation of the clock may be secured, as will be presently described. 90 Said wheel or ring is partially filled with mercury or other liquid, as indicated in Fig. 1. Said wheel or ring is adjustably secured on the lower side of the ring B and connected to

A metal plate B³ is adjustably secured on the lower side of the ring B and connected to

one line-wire 13 of an electrical circuit. Below the same, secured on the frame, is a graduated scale C, having a contact-finger c, adjustably mounted thereon, which is connected 5 to the other line-wire 14 of said circuit. Said wires run to opposite poles of the battery 15. By adjusting said metal plate B³ or said contact-finger, or both, alarm or call bells located in said circuit will be sounded at the intervals desired, as will be readily understood.

The operation of my said invention is as follows: The parts being in the relative position shown and the magnet 6 being energized by the closing of the circuit by means of the 15 contact-arm 9, as above described, the armature end of lever 5 is suddenly pulled down, the rack-bar 4 forced up, rotating the toothed wheel 2, which carries the ring or wheel B with it to that point where the arm 9 will pass 20 one end of the rib b⁴, when it will spring over onto the non-conducting surface b⁵ on the opposite side and break the circuit. A portion of the mercury or other liquid in the ring B at the same time passes through the by-way B' from 25 chamber b' to chamber b² to maintain its level, and as said by-way is now in the position indicated by dotted lines in Fig. 1 the liquid cannot return through said by-way. The weight W now operates to reverse the motion of wheel 30 B, but the weight of the liquid in chamber b² nearly balances it and retards its motion. The valve b being adjusted to just the required degree will, however, permit the liquid to flow back into chamber b' at the speed 35 required to move the hand H the distance desired during the period of time predetermined, the movement being effected through the ratchet-wheel 3 and pawl p, as will be readily understood. When the weight has turned 40 said wheel on its axis until the point of arm 9 passes the other end of rib b⁴, it springs back to the other side, closes the circuit through magnet 6, and energizes the same, forcing said wheel B back quickly, as before described, and this operation will continue indefinitely. Call or alarm bells being located 45 in the circuit composed of the wires 13 and 14 and battery 15 will be sounded as the contact-finger c comes against the surface of the metal strip B³ and closes said circuit, as will be readily understood. By the adjustment of said finger c on the scale C the time of sounding said bells may be determined as desired.

55 Instead of a single wheel B, as shown, a series of them may be mounted on a single shaft and an increase in motive power thus obtained and the continuous operation of the clock insured, as if one wheel should get out 60 of order the others would continue to drive the shaft.

Having thus fully described my said invention, what I claim as new, and desire to secure by Letters Patent, is—

65 1. In an electric clock, the combination of an oscillating wheel divided by a valve at its bottom and connected by a passage above

said valve and containing fluid, an electric mechanism for oscillating said wheel in one direction, and means for operating it in the opposite direction by gravity against the weight of the fluid, which is permitted to flow through said valve, and the clock and indicating mechanism, substantially as set forth.

2. In an electric clock, the combination of the wheel containing liquid and mounted to oscillate on a shaft, said shaft, indicating-hands thereon, electrically-operated mechanism for operating said wheel in one direction, a weight for operating it in the other, a clutch mechanism connecting the chamber and the shaft to operate said shaft when said wheel is operated by said weight, and a valve in said wheel for regulating the flow of the liquid therein from one side to the other, substantially as set forth.

3. In an electric clock the combination of a pivoted annular chamber divided into sections, and having a passage extending from one side to the other above its lower portion, permitting the fluid to flow freely from one section to the other when the chamber is tilted in one direction; a gravity driving device for moving the said chamber in the reverse direction, and means for controlling the flow of fluid from one section to the other while the chamber is being moved in the reverse direction, thereby regulating the speed of the said chamber, substantially as set forth.

4. In an electric clock the combination, of a shaft, an annular hollow wheel, mounted thereon, a regulating-valve dividing the chamber into sections, a pipe or passage connecting the two sections and arranged above the said valve, and means for oscillating the said chamber, substantially as set forth.

5. In an electric clock the combination of an oscillating hollow wheel for fluid, divided into sections and provided with means for regulating the distribution of the fluid in the said sections; of an electromagnet, intermediate mechanism between the said electromagnet and chamber whereby the said chamber is tilted in one direction when the electromagnet is energized, and a circuit making and breaking device operated by the said chamber and controlling the current through said electromagnet, substantially as set forth.

6. In an electric clock, the combination, of a pivoted chamber for fluid divided into sections and provided with means for regulating the distribution of the fluid in the said sections: of an electromagnet and intermediate mechanism operating to tilt the said chamber in one direction; a weight for moving the said chamber in the reverse direction; and a circuit making and breaking device controlling the said electromagnet and operated by the said chamber, substantially as set forth.

7. In an electric clock, the combination, of an oscillating hollow wheel containing fluid and divided into sections, a regulating-valve between said sections, a shaft carrying the in-

dicating hands, a clutch connecting said wheel and shaft to operate together in one direction, a magnet and gear arranged to operate said wheel in one direction when said 5 magnet is energized, an electric circuit, a circuit maker and breaker operated by said wheel, and gravity mechanism for operating said wheel when said circuit is broken, substantially as set forth.

10 8. The combination, of an oscillating chamber, a valve dividing it, electric mechanism

for operating it in one direction, gravity mechanism for operating it in the other, and a circuit maker and breaker controlled thereby, substantially as set forth. 15

In witness whereof I have hereunto set my hand and seal, at Baltimore, Maryland, this 3d day of May, A. D. 1899.
